CALCULATOR FOR DETERMINING STARCH CONSUMPTION IN THE PRODUCTION OF CORRUGATED PAPER BOARD

John De Ligt, Covington, Va., assignor to
Westvaco Corporation, New York, N.Y.

Filed Sept. 13, 1974, Ser. No. 505,921

Term of patent 14 years

Int. Cl. D19—99

U.S. Cl. D64—11 B

FIG.1

FIG.2

FIG.3

FIG. 1 is a top plan view of a calculator for determining starch consumption in the production of corrugated paper board, showing my new design.

FIG. 2 is a right edge elevational view; and

FIG. 3 is a front edge elevational view.

The back of the claimed calculator is unornamented. The back surface is level except that, as shown in FIG. 2 and in FIG. 3, a nut and bolt in assembled form extend from the surface thereof.

I claim:

The ornamental design for a calculator for determining starch consumption in the production of corrugated paper board, substantially as shown and described.
